INVENTOR

W. W. Lillard

UNITED STATES PATENT OFFICE.

WILLIAM W. LILLARD, OF JERSEY CITY, NEW JERSEY.

GAME.

Application filed April 14, 1921. Serial No. 461,438.

To all whom it may concern:

Be it known that I, WILLIAM W. LILLARD, a citizen of the United States, and a resident of Jersey City, in the county of Hudson and State of New Jersey, have invented a new and Improved Game, of which the following is a full, clear, and correct description.

The invention relates to games played with objects moved about on a board having divisions or squares and particularly to a game called chess that is played by two persons on a board having sixty-four squares, each person or player ordinarily having sixteen chessmen, eight pieces and eight pawns.

One object of the invention is to change or modify the above mentioned chess game to make it a more accurate image of a battle between armed forces of the present time. Another object is to introduce a small element of chance in this new chess game in a manner that will increase the interest in the game, especially for young persons.

With these and other objects in view, the invention consists of certain novel features used in combination with the well known chessmen on a chessboard as hereinafter shown and described and then specifically pointed out in the claims.

It will be understood that in this application for Letters Patent the term "chessman" will mean any piece or pawn ordinarily used in playing the game of chess. And the term "chessmen" will mean the eight pieces and eight pawns commonly used in chess games or any part of the total number of pieces and pawns when they are considered as one body or group.

A practical embodiment of the invention is shown in the accompanying drawings forming a part of this specification, in which similar characters of reference indicate corresponding parts in all the views.

Figure 1 is a partial plan view of a chessboard with some of the pieces and some of the pawns inside individual cases or covers.

Figure 2 shows sectional views of chessmen in individual cases or covers.

Figure 3 is a top view of a case or cover adapted to enclose any piece or pawn.

Figure 4 is a plan view of an identity plate, one of which is used in connection with each one of the chessmen, excepting the king pieces.

Figure 5 is a plan view of an identity disc or card, one of which is used in connection with each one of the cases shown in Figures 2 and 3.

Figure 6 is a sectional view of an identity disc and identity plate, the former being in place in a recess in the top side of the latter.

Figure 7 is a top view of the same.

Figure 8 is a plan view of an arrangement of an identity disc in place in an identity plate whereby the former serves as a case and the latter as a chessman.

Figure 9 is a front view of a form of chessman that is commonly used in sets of "pocket chess."

Figure 10 is a side view of the same.

Figure 11 is a front view of the same with a case or cover on it to conceal the identity of the chessman, i. e., the picture of the chessman.

The game of chess is generally considered to resemble more closely than any other well known game the actions and movements of armed forces in battle. Battles of the present age, however, are fought quite differently in some respects from those of ancient times when the game of chess was first devised and played. In the wars of modern times, just before an important battle is to be fought, much thought and effort is given by the commanders of the opposing armies to the problem of placing the different elements of their forces in the most advantageous positions. This is done, if possible, before any severe fighting begins and much pains are always taken to prevent the enemy from learning the strength and location of the various bodies of the opposing army. Since the invention of the aeroplane, the moving of troops to their battle position is usually done at night or through woods or in some way that the enemy aeroplane operators and observers can not see them.

It will be at once admitted by any experienced chess player that one important phase of a modern battle, of placing the different bodies of the armies in advantageous battle positions, unobserved by the enemy, is not exemplified or shown in the game of chess as it is now played. In the invention of applicant, the object of a player to position his chessmen in advantageous locations unawares to his opponent is accomplished by providing an opaque case or cover for each of the chessmen which will

hide them from view yet allow them to be moved from square to square as readily as if they were not inclosed in cases. To enable a player to always be certain of knowing what case a particular chessman is in or under without having to resort to a severe trial of memory, each case has its individual mark by which it can be known. Then if a simple memorandum is kept showing what piece or pawn is in a case of a certain mark, and this system is carried out with the other cases, a player can always know the kind of chessman in each case and his opponent will not except in certain cases hereinafter explained.

Referring to the drawings, 11 represents a playing board such as is commonly used in playing games of chess or checkers. 12 represents chessmen of a kind in common use. 13 are opaque cases or covers adapted to be placed over any of the chessmen 12, and will conceal the identity or character of the chessmen when so used. Each of the cases 13 will have its individual mark 23 which will preferably be a letter of the alphabet or a figure. Any of the cases 13 can be used with any of the chessmen 12, although it is not intended that a case be placed over the king of either player. 14 represents a chessman identity plate, the use of which is explained below. There will be an identity plate 14 for each one of the chessmen 12, except the kings. It will be understood that the kings can be played under cases and in such event identity plates 14 for the kings would be needed. Each identity plate 14 will be suitably marked, preferably by a picture of a pawn or some particular piece to show what kind of chessman it stands for or represents. Each identity plate 14 will be alike in size and appearance all the others except for its individual identity mark, i. e., picture. 15 is a case identity card or disc. There will be one identity disc 15 for each case 13 and a disc 15 will have the same kind of individual mark 23 that the case 13 has which it represents, as explained below.

Referring to Figure 2, 16 are chessmen having special features making them well adapted for use with cases in applicant's new chess game. 17 is a tapered section near the base of the chessmen designed to fit snugly with a wedging effect in the case 13. Thus the case 13 and the chessman 16 can be moved as one piece. 18 is a bead or fillet on the base of the chessman 16 to allow the chessman to be conveniently grasped by the fingers for removing it from the case 13. 19 is a bead or fillet section at the top of the cases 13 which is desirable that the cases can be conveniently handled and moved about on a chessboard. It will be noted that the tapered section 17 on a pawn 65 is the same size as that on a piece and as

the internal diameter of all the cases 13 will be the same, it will be seen that any case 13 can be used on any chessman 16 whether it be a piece or pawn since each case 13 will be made deep enough to cover the tallest chessman. The external dimensions of all the cases will preferably be the same, though this is not entirely necessary. The design and outward appearance of all cases 13 of one player will preferably be the same though this is not entirely necessary.

Referring to Figures 4, 5, 6, 7, and 8, the chessman identity plate 14 and the case identity disc 15 are shown in Figure 7 as they will be ordinarily used, i. e., as an identity plate and identity disc for a purpose explained hereafter. It will be noted that in Figure 7 the identity disc 15 is shown with its lettered face down. Figure 8 shows the identity plate 14 and the identity disc 15 when serving as substitutes for, respectively, a chessman 12 and a case 13. In Figure 8, the lettered face of the identity disc 15 is up. Thus it will be seen that the identity plates 14 and the identity discs 15 can be used together in two different ways. Also, the chessmen identity plates 14 can be used as substitutes for chessmen in playing the regular chess games or in solving chess problems.

Referring to Figures 9, 10, and 11, 112 is a form of chessman designed for use in sets of "pocket chess." It will preferably be a thin piece of card board or other suitable material with a picture of a chessman on its upper end. 113 is a case or cover adapted for use with the chessman 112. It will be noted that the case 113 extends down over the chessman 112 only far enough to cover the picture 114. The case 113 will preferably be made as a kind of envelope of opaque paper or similar material.

It will be understood that all of the different devices described above for use in playing the modified chess game of applicant will be divided preferably into two groups; one being of a different color from the other.

In playing the modified chess game of the applicant, each player, at the beginning of a game, will be allowed to position his chessmen in his first two ranks or rows of squares in any order he chooses. He can put all of his pawns in his first rank, if he sees fit to do so, which of course is not likely. At the beginning of a game, all of the chessmen of each player, excepting their kings, will preferably be in or under the cases or covers 13. While a chessman is in a case, it will have only the moving rights and powers of a pawn. When a piece is removed from its case, it will have the same moving rights and powers and privileges that it has in the regular chess game. To remove a chessman from its case before both players have made

their twelfth move will count as the regular move of the player doing it and he can not move again until his opponent moves. After the second player, i. e., the one who did not move first at the beginning of the game, has completed his twelfth move, each player can remove all or as many of his own chessmen as he chooses from their cases. This period when the chessmen are being uncased will be hereinafter called the "zero hour" period of the game. Any chessman removed from its case after the zero hour period will count as the move for player doing it.

13 In playing the modified chess game of the applicant, it will often be very advantageous to a player to learn the identity, i. e., the exact kind of chessman in a certain case of his opponent. It will be understood that 18 when a player places a chessman in a certain case he will do it in such a way that his opponent will not see what particular chessman goes in that particular case. A means is provided whereby either player can have 23 an opportunity of learning the identity of some of his opponent's chessmen while still in their cases. This is accomplished in the following manner. Each player after placing a chessman 12 in a case 13, will place on the chessman identity plate 14 which represents the chessman just encased the identity disc 15 that has the same identifying mark as the case 13 just used for encasing the chessman 12. The identity disc 35 will be placed with its marked face down as shown in Figure 7 and the identifying marks on both the disc 15 and the plate 14 will be hidden from sight. These sets of discs 15 and plates 14, as shown in Figures 40 6 and 7, will be placed to one side and each player can pick out not exceeding six sets of his opponent's discs and plates and examine them, thereby learning what particular kind of chessmen are under certain of 45 his opponent's cases. To secure the right to examine the above described sets of discs and plates belonging to his opponent, a player will forfeit or remove from his chessmen on the chessboard one of his pawns for 50 each of the three sets examined.

It will be understood that in playing applicant's game, that it is quite practicable to use the cases 13 for the purpose described without using the identity case discs 15 and 55 the identity plates 14. Also various substitutes for the discs 15 and plates 14, as shown, can be devised. For example, the name of a chessman and the mark of its case can be written on a piece of paper and placed in an envelope. The use of such a substitute, clearly does not depart from the spirit of the invention.

It will be further understood that the applicant does not limit his invention to the 60 particular methods and rules of playing his

new game as are noted above. For example, the cases can, by agreement between two players, be removed from all the chessmen when each player has completed his sixth move.

70 Except as described and explained above, the game of the applicant will preferably be governed by and played according to the rules, customs, and laws that apply to the well known game of chess.

75 It will be understood however that the applicant does not limit the use of the identity concealing cases, identity plates, and identity discs to the modified game of chess as described above.

80 Having thus described my invention, what I claim as new and desire to secure by Letters Patent is:—

1. In a game played with chessmen, individually marked means for concealing the 85 identities of certain chessmen.

2. In a game played with chessmen, individually marked, opaque cases adapted to conceal the identities of certain of said chessmen.

90 3. In a game played on a checkerboard, in combination, chessmen and individually marked, movable means for concealing the identities of certain of said chessmen.

4. In a game played on a board having 95 divisions, in combination, game pieces of different playing value and individually marked, movable means adapted to conceal the identity of certain of said game pieces.

5. A set of chessmen comprising various 100 pieces and pawns of different forms and sizes, each of said chessmen being mounted on a tapered base element and all of said base elements having the same form and size.

105 6. In combination, a set of chessmen comprising various pieces and pawns, as commonly used, each of said chessmen being mounted upon a tapered base element, all of said base elements having the same form and size and individually marked cases adapted to inclose said chessmen and fit closely about said tapered base elements.

110 7. In a game played with a plurality of objects of different playing value, a plurality of movable means adapted for concealing the playing value of certain of said objects, each of said means having a different identifying mark from the others.

115 8. In a game, a set of chessmen, a plurality of movable means adapted for concealing the identities of certain of said chessmen, each of said means having an identifying mark.

120 9. In a game, a set of chessmen, a plurality of movable means adapted for concealing the identities of certain of said chessmen, each of said means having a different identifying mark from the others.

125 10. In a game, in combination, a set of

chessmen and a plurality of movable, opaque objects adapted for concealing the identities of certain of said chessmen, each of said objects having a different identifying mark from the others.

11. In a game, in combination, a set of chessmen and a plurality of movable, opaque cases adapted to inclose certain of said chessmen, each of said cases having a different identifying mark from the others.

12. In a game, a set of chessmen and a plurality of movable, opaque cases, each of said cases having a different identifying

mark from the others, said chessmen comprising two king pieces and a plurality of other pieces and pawns, said cases adapted to inclose any of said chessmen except the said king pieces.

Signed at Jersey City, in the county of Hudson and State of New Jersey, this 12th day of April, A. D. 1921.

WILLIAM W. LILLARD.
